UNITED STATES PATENT OFFICE.

WASHINGTON I. TUTTLE, OF BALTIMORE, MARYLAND, ASSIGNOR TO TIN DECORATING COMPANY OF BALTIMORE, OF BALTIMORE, MARYLAND, A CORPORATION OF NEW JERSEY.

SHEET-DRYING APPARATUS.

1,198,878.

Specification of Letters Patent. Patented Sept. 19, 1916.

Application filed October 24, 1914. Serial No. 868,351.

To all whom it may concern:

Be it known that I, WASHINGTON I. TUTTLE, a citizen of the United States, residing at Baltimore, in the State of Maryland, have invented new and useful Improvements in Sheet-Drying Apparatus, of which the following is a specification.

This invention relates to certain novel and useful improvements in drying apparatus, and while the invention involves improvements in drying apparatus in general, I have described the invention in the following specification as applied to the manufacture of printed "tins" or sheets of metal used largely in the manufacture of metallic containers. The sheets or blanks from which such metal containers are made are frequently printed in several colors. The application of each color necessitates a separate printing operation, and after each printing the tins or sheets must be dried or baked in order to render the printing effective and to cause the color to adhere. In the practical manufacture of these printed blanks, they are handled in great quantities and the handling necessary to reprint and re-dry the sheets greatly increases the labor involved.

A principal object of the present invention is to provide apparatus which will greatly facilitate the handling and drying and rehandling and re-drying of such articles in large quantities.

A further object of the invention is to provide an arrangement whereby the attendants of the apparatus are not exposed to a high temperature, and to arrange the apparatus in such a way that the loading and unloading of the articles passing into and out of the drier can be readily accomplished.

A further object of the invention is to provide an arrangement whereby the articles being dried will be methodically heated.

A further object of the invention is to provide apparatus including a drying chamber or oven, and having means particularly adapted for passing and repassing articles through the drying chamber or oven in large quantities, and to provide an arrangement which economizes space in the building used for the purpose.

Further objects of the invention will appear more fully hereinafter.

The invention consists in the general combination of parts and features hereinafter described, all of which contribute to produce an efficient drying apparatus.

A preferred embodiment of my invention will be particularly described in the following specification, while the broad scope of my invention will be pointed out in the appended claims.

In the drawings:—Figure 1 is a diagrammatic plan partly in section and partly broken away showing a dry house with the preferred arrangement of drying apparatus therein. Fig. 2 is a vertical section partly broken away, further illustrating the preferred arrangement of the apparatus. Fig. 3 is an elevation upon an enlarged scale partly in section and partly broken away, and further illustrating the means for driving and guiding the endless conveyers which are a feature of the invention. Fig. 4 is an elevation illustrating the arrangement for bringing the articles to be dried, such as the tins, from auxiliary apparatus, such as printing presses, so as to enable the articles to be passed or repassed through the drying chamber. Fig. 5 is a side elevation and partial section illustrating a belt tightener in detail, which forms a part of the apparatus shown in Fig. 4. Fig. 6 is a section partially broken away and further illustrating the arrangement for guiding and drying the apparatus shown in Fig. 4. Fig. 7 is a plan of one of the racks which constitutes a feature of the invention and upon which the articles are loaded in passing the same into the drying chamber. Fig. 8 is a front elevation of one of the racks, only a portion of which is represented as completed, but which illustrates the construction of these racks. Fig. 9 is a side elevation and partial section further illustrating the construction of the racks for carrying the articles to be dried. Fig. 10 is a side elevation partly broken away, showing details of the preferred construction. Fig. 11 is a fragmentary side elevation of an arm for guiding the racks. Fig. 12 is a plan of the guide arm and indicating how it guides the racks.

Referring more particularly to the parts, 1 represents the working floor of a dry house, having a roof 2; the drying chamber 3 is preferably in the form of a shaft or oven the walls of which extend down from the roof 2, the lower end 4 of the drying chamber being preferably open and disposed at an elevated point above the working floor 1. This lower end 4 is most conveniently 10 placed just above the beams 5 which afford means for the attachment of hangers 6 for supporting a working platform 7 which is located between the working floor 1 and the opening 4.

16 The drying chamber is preferably placed in a central bay, the roof 2 whereof may have skylights 2^a and ventilators 2^b in the sides of any suitable type such as the transom ventilators indicated. Above the roof

20 the side walls of the drying chamber are preferably provided with side ventilators 2^c which may be of any desired type preferably arranged to be opened and closed from below by any means such as cords 2^d.

26 I provide for passing the articles to be dried up into the interior of the drying chamber, and I provide for the loading and unloading of the articles to be dried from the working floor 1 and platform 7. I also

30 prefer to provide an arrangement for enabling the articles to be passed and re-passed up into the drying chamber. For this purpose, I prefer to provide a plurality of conveyers A, B, C, D, arranged end to end

36 along one of the side walls 8 of the drying chamber, and opposite to these conveyers, I prefer to provide a similar set of conveyers A', B', C', D'. These conveyers are preferably of the endless conveyer type. They are 40 similar in construction so that a description of a pair of them will suffice for all.

Referring now, particularly to Figs. 1 and 3, each conveyer preferably comprises a pair of endless chains 9 the upper ends of 45 which pass around oppositely disposed pairs of sprocket wheels 10; the sprocket wheels 10 of the conveyer A' are disposed opposite to the sprocket wheels 10 of the conveyer A. The lower ends of the chains 9 pass 50 around guide wheels or sprocket wheels 11, the shafts of which are mounted in suitable bearing blocks 12, and these bearing blocks are secured between two suitable vertical guides preferably consisting of two parallel bars 13.

55 Between the chains 9 of each conveyer, I prefer to provide a plurality of racks or cars 14, the preferred construction of which is illustrated in Figs. 7 to 9. These racks 60 preferably comprise backs 15 formed of a substantially rectangular frame presenting vertical bars 16 arranged in pairs, and intermediate vertical bars 17. The lower ends 65 of the bars 16 and 17 are attached to a bottom rail 18. On one side of the back

15, I provide a plurality of holders 19 for the articles which are to be dried, and these holders are preferably arranged in transverse horizontal rows and are preferably in the form of skeleton brackets or shelves formed of bars bent into substantially U-form, (see Fig. 7). The rear ends of the sides 19^a of these frames or holders 19 pass through openings in the forward flange 20 of the bars 16 which are of channel form, and beyond the flanges these ends are off-set and anchored or riveted in the back flange 21 of the bar 16.

70 Near the middle points of the holders or frames 19 I prefer to provide braces 22 which are attached to the faces of the intermediate vertical bars 17. As viewed in side elevation, as shown in Fig. 9, the holders 19 all incline upward slightly toward their outer ends.

75 At the upper end of each rack and near the ends thereof, I prefer to provide outwardly projecting arms 23, and on the under sides of these arms I provide brackets 24 which support a spindle or rod 25 which extends longitudinally over the rack at about the middle point of the holders or shelves 19. In order to brace this bar and the bracket, I prefer to provide inclined tie bars 26 at each end of the rack, the lower ends of which are anchored in the bottom rail 18 and the upper ends of which pass through the arms 23 and are threaded so as to receive clamping nuts 27 which clamp the tie rods to the end of the arms.

80 At points intermediate of the shelves or holders 19, I prefer to provide a plurality of vertical guard bars 28 which prevent the articles, when on the holders, from slipping laterally. These bars are preferably held in 105 position by suitable brackets 29.

85 The ends of the suspending bar 25 have gudgeons or pintles 30 which are pivotally supported on opposite links 31 of the chains 9, (see Fig. 10). The racks are attached a sufficient distance apart to enable them to swing clear of each other when the conveyer is in motion. The gudgeons 30 are disposed forward of the frame or back of each rack so as to be nearly over the center of gravity of the loaded rack, and this arrangement prevents undue forward tilting of the rack after being loaded.

110 The conveyers are preferably driven intermittently in the direction indicated by the arrows in Fig. 3. In order to accomplish this, each sprocket wheel 10 is rigid with a gear wheel 32; said gear wheel being driven by a pinion 33 rigid with a worm wheel 34, said worm wheel being driven continuously by a worm 35; the worms 35 are disposed on cross shafts 36 and these shafts are driven by gears 37 from longitudinal shafts 38 disposed on each side of the drying chamber.

By reason of the manner in which the racks 14 are arranged on the conveyers, it will be seen that as they descend at their inner runs 39 of the chains, the backs 15 of the racks on one conveyer are disposed adjacent to the backs of the racks on the opposite conveyer. In other words, the racks are back to back. This arrangement economizes space by enabling the conveyers to be placed closely together, and furthermore, it coöperates to bring about the methodic heating referred to above. In order to effect this methodic heating, I prefer to provide heating devices 40 preferably in the form of heating coils which may be steam coils or similar heating apparatus, or electrical heating devices, if desired. These heating devices 40 are preferably placed between the two runs of each conveyer. On account of this arrangement, it will be seen that as the racks ascend, the backs are toward the heating devices and the articles are exposed toward the outer side or wall of the drying chambers. As the racks descend, near the middle plane of the drying chamber, the holders on the racks project toward the heaters. In this way, the articles being dried are gradually heated as they enter and ascend into the drying chamber, and they are made to pass between the sets of heating devices just before they make their exit from the drying chamber, and this of course, will be the hottest point along their route of travel. As the cars pass the working floor 1, they are preferably unloaded and the articles placed upon trucks such as indicated by the numeral 41, said trucks being mounted upon tracks 42 which extend longitudinally of the drier so as to run past the presses *a*, *b*, *c* and *d*, on one side of the dry house, and similar presses *a'*, *b'*, *c'* and *d'* on the other side. These presses are disposed preferably equidistant and are provided with any suitable arrangement for printing the colors on the tin sheets. The tins or sheets, after being printed, are preferably loaded upon the racks suspended from the conveyers, by an attendant standing on the platform.

I provide means for delivering the printed sheets or tins to the attendants on the platform 7, for which purpose I prefer to provide each press, such as the press *a'* in Fig. 4, with a conveyer attachment 43 which may comprise a conveyer chain 44 having equidistant dogs 45 which engage the sheets or tins 46 and advance them upwardly on a track or incline 47 so as to deposit them on a continuously moving substantially horizontal conveyer belt 48. There are a plurality of these belts 48 corresponding to the different conveyers A, B, C, etc. The conveyers 43 as well as the conveyer belts 48 may be driven from a moving shaft 49 of their corresponding parts. From this shaft 49, a chain 50 is preferably arranged to drive a gear wheel 51, said gear wheel being in mesh with a gear wheel 52 carried on an arm 53 radially disposed and adapted to be secured in any position desired by a clamp 54. The gear wheel 52 is rigid with a sprocket wheel 55 under which the chain 44 passes, so that the arm 53 and this sprocket wheel 55 operates as a chain tightener. The sprocket wheel 55 drives the chain 44. As each horizontal conveyer 48 is driven from its corresponding press, when certain color presses are shut down their corresponding conveyers also stop.

The arm 53 is preferably clamped to a bushing 56 which is rigid in the frame 57, (see Fig. 6,) and which forms a bearing for the shaft 58 which carries the gear wheel 51, and this shaft 58 also carries a sprocket wheel 59 over which runs a chain 60, to drive the conveyers 48 through the medium of beveled gears 61, it being understood that the belt 48 passes around rollers, the shafts 62 of which are driven directly from the bevel gears 61 in some such manner as indicated in Fig. 4.

The printed sheets or tins issue from the press rolls *a*² and *a'*³ and pass across a guide plate *a*⁴ onto rollers *a*⁵ which start the sheets in succession up the incline 47 and bring them into a position such that their rear edges will be engaged by the dogs 45.

In order to guide the racks and hold them against swinging while they are being loaded, I prefer to provide guide arms 14^a which may project out from the vertical guides 13 and these arms are preferably provided with rollers 14^b which engage the channels 14^c on the ends of the racks 14.

The printing presses *a*, *b*, *c* and *d*, and *a'*, *b'*, *c'*, and *d'* are preferably disposed near the side walls 63 of the dry house.

The aforesaid shafts 38 which drive all the conveyers are preferably both driven from a suitable motor 64, Fig. 1, the driving pinion 65 of which drives a gear wheel 66 on the shaft 67, said shaft being arranged to drive oppositely disposed sprocket chains 68, the outer ends of which pass around sprocket wheels 69 on the shafts 38.

The general mode of operation of the drying apparatus will now be set forth.

The sheets to be dried are loaded individually onto the shelves of the racks 14 by operators or attendants standing on the elevated platforms 7, the conveyers being driven at a slow rate of speed and intermittently; as the racks reach the lower limit of their descent, they lie near the working floor 1, at which point the operators or attendants remove the dried sheets and place the same on trucks such as the truck 41. This truck is then passed along on the tracks and the sheets or tins are taken from it and fed to the next press. Passing from the

- presses the sheets are fed successively upwardly to the platform 7 and onto the horizontal conveyers 48 which are continuously moving and carry the sheets longitudinally 5 of the holders or shelves of the racks. The attendants on the platforms 7 can conveniently handle a great number of sheets in this way, lifting them from the conveyers 48 to the racks.
- 10 Attention is called to the fact that the mechanism for driving the conveyers is preferably removed from the point at which the operators stand, which is a feature making for safety in operation.
- 15 On account of the fact that the lower end of the drying chamber or oven is elevated above the floor, and on account of the further fact that there are no doors at this point, the oven tends to maintain a constant 20 temperature and insures that the heating will be carried on methodically.
- 25 The arrangement set forth for loading and unloading the sheets, at different levels, by reason of the working floor, and the elevated platform, greatly facilitates the handling of large quantities of sheets expeditiously, and attention is called to the fact that the operators are all below the drying chamber which prevents their being directly 30 exposed to the hot air which tends to rise in the drying chamber.
- 35 The apparatus described above utilizes space which is principally overhead space, and which in some aspects is to be regarded as waste space.
- 40 In operating the apparatus the ovens are of sufficient height and the speed of the conveyers is such that all the output of printed tins from the presses can be accommodated through each cycle of printing and redrying.
- 45 The side walls of the oven shaft 3 are preferably of heat resisting material such as asbestos. The ventilators 2^a afford a direct outlet from the shaft to the outer air and insure a slight upward movement of the air in the oven shaft which is highly desirable because it insures that the air, where the men are working, will remain comparatively cool. The skylights 2^b throw light 50 directly onto the platforms 7. The ventilators 2^b enable the hot air adjacent the shaft 3 and under the roof to escape and this assists in keeping down the temperature in the room or compartment.
- 55 Although I have described the upper end of the drying chamber as extending above the roof, it need not so extend.
- 60 Although I have described the apparatus as of a duplex construction involving the use of opposed pairs of conveyers, of course, if desired, the conveyers need not be used in opposed pairs but can consist of a single, instead of a duplex, conveyer.
- 65 It is understood that the embodiment of the invention described above is only one

of the many forms or embodiments the invention may take, and I do not wish to be limited in the practice of my invention nor in my claims to the particular embodiment set forth.

70 What I claim is:—

1. An apparatus of the class described comprising a compartment having a working floor, an endless conveyer extending upwardly from a point near the floor, an elevated drying oven surrounding said endless conveyer, a plurality of racks carried by said conveyer, an elevated platform, and means for driving the conveyer to carry the racks successively through the oven and bring them to loading and unloading positions relative to the platform and the floor. 75
2. An apparatus of the class described, comprising a compartment having a working floor, an endless conveyer extending upwardly from a point near said floor, an elevated drying oven surrounding said conveyer, a platform between the floor and the lower end of said oven, a plurality of racks carried by the conveyer, and means for driving the conveyer to carry the racks successively through the oven and bring them to loading and unloading positions relative to the floor and the platform. 80
3. An apparatus of the class described comprising a compartment having a working floor, an endless conveyer extending upwardly from a point near the floor, an elevated drying oven through which the endless conveyer travels, an elevated platform located between the floor and the lower end of the oven, a conveyer for transferring sheets from a point adjacent to the floor to the platform, and means above the platform and below the bottom of the oven for conveying sheets in a plane substantially parallel with the platform. 85
4. A drying apparatus comprising a room or compartment having a working floor and an oven shaft in the upper part of the room or compartment, said shaft being open at its lower end, an endless conveyer movable vertically in the oven shaft, a plurality of racks suspended from the endless conveyer, each rack provided with sheet supporting shelves, and means for moving the endless conveyer to cause the racks to travel through the oven shaft and to be brought successively to exposed loading and unloading positions below the open end of the oven shaft. 90
5. A drying apparatus comprising a room or compartment having a working floor, a drying oven in the upper part of said room or compartment, the lower end of said oven terminating at a point above the said working floor, an endless conveyer movable upwardly in said oven, racks carried by said conveyer, and means for driving the conveyer to carry the racks successively through the oven and bring them to loading and unloading positions relative to the floor and the platform. 95

loading positions below and outside the said oven.

6. A drying apparatus comprising a room or compartment having a working floor, a drying oven in the upper part of said room or compartment, the lower end of said oven being spaced apart from said working floor, an endless conveyer movable upwardly in said oven, racks carried by said conveyer, an elevated platform and means for driving the conveyer to carry the racks successively through the oven and bring them to the loading or unloading positions relative to said floor or said platform.

7. A sheet drying apparatus comprising a room or compartment having a working floor, a drying oven in the upper part of said room or compartment, said oven being spaced apart from said working floor, an endless conveyer having two endless chains within said drying chamber, sprocket wheels within said drying chamber over which said endless chains pass, means for driving said sprocket wheels to actuate said conveyer, a plurality of racks carried by said conveyer adapted to move in succession past a loading point between the floor and the lower end of said oven, and a heater within said oven disposed between the runs of said chains.

8. A sheet drying apparatus comprising a room or compartment having a working floor, a drying oven in the upper part of said room or compartment, said oven having its lower end at a point above and spaced apart from said working floor, an endless conveyer mounted in said drying oven and having one of its runs disposed toward one side of the drying oven, a second endless conveyer in said oven opposite said endless conveyer and having one of its runs disposed toward the opposite side of said oven, a plurality of racks attached to said endless conveyer, said conveyers extending below the lower end of said oven so as to carry the racks successively past loading and unloading points between said floor and the lower end of said oven.

9. A sheet drying apparatus comprising a room or compartment having a working floor, a drying oven in the upper part of said room or compartment, said oven having its lower end at a point above said working floor, an endless conveyer mounted in said drying oven and having one of its runs disposed toward one side of the drying chamber, a second endless conveyer in said drying oven opposite said endless conveyer and having one of its runs disposed toward the opposite side of said oven, a plurality of racks attached to said endless conveyer, said conveyers extending below the lower end of said oven so as to carry the racks successively past loading and unloading points between said floor and the lower end of said oven, and heating devices disposed

respectively between the runs of said conveyers for heating the interior of said oven.

10. A sheet drying apparatus comprising a room or compartment having a working floor, a drying oven in the upper part of said room or compartment, said oven terminating at a point above the said working floor, and endless conveyers within said oven, a plurality of racks carried thereby, said cars having backs and a plurality of holders for the said sheets projecting from said backs on one side thereof, means for actuating and guiding said conveyers so that said racks ascend into said drying oven from a point below the lower end along the outer side of the said oven, and descend adjacent the middle plane of the said oven, the backs of the racks of oppositely disposed conveyers being disposed adjacent as they descend.

11. A sheet drying apparatus comprising a room or compartment having a working floor, a drying oven in the upper part of said room or compartment, said oven terminating at a point above the said working floor, a plurality of endless conveyers within said oven, a plurality of racks carried thereby, said racks having backs and a plurality of holders for the said sheets projecting from said backs on one side thereof, means for actuating and guiding said conveyers so that said racks ascend into said drying oven from a point below the lower end thereof along the outer side of the said oven and descend adjacent the middle plane of the said oven, the backs of the racks of oppositely disposed conveyers being disposed adjacent as they descend, and heaters on each side of the middle plane of said drying chamber, said holders being arranged to project toward the said heaters as they move past the same.

12. A sheet drying apparatus comprising a room or compartment having a working floor, a drying oven in the upper part of said room or compartment, the side walls of said oven terminating at a point above the said working floor, an endless conveyer movable vertically upwardly in said oven, racks carried by said conveyer, and means for driving the conveyer to carry the racks successively through the oven and bring them to loading and unloading positions below and outside the said oven.

13. A sheet drying apparatus comprising a room or compartment having a working floor, a drying oven in the upper part of said room or compartment, the said oven being open at its lower end and the side walls of said oven terminating at a point above and spaced apart from the said working floor, an endless conveyer movable vertically upwardly in said oven, racks carried by said conveyer, and means for driving the conveyer to carry the racks successively

through the oven and bring them to loading and unloading positions below the open end of the oven.

14. A drying apparatus comprising a room or compartment having a working floor, a drying oven in said compartment having its lower end terminating above and spaced apart from said floor, a plurality of racks for carrying the articles to be dried, means for advancing and guiding said racks upwardly into the interior of said oven and downwardly below the lower end thereof to enable the racks to be loaded and unloaded between the lower end of the oven and said working floor, and means for heating the air on the interior of said oven, said oven having communication with the outer air near the upper end thereof whereby a slight upward movement of air is developed in said oven to maintain a relatively cool temperature near the loading and unloading positions between the floor and the oven.

15. A drying apparatus comprising a room or compartment having a working floor, a drying oven in said compartment having its lower end terminating above said floor, a plurality of racks for carrying the articles to be dried, means for advancing and guiding said racks upwardly into the interior of said oven and downwardly below the lower end thereof to enable the racks to be loaded and unloaded between the lower end of the oven and said working floor, an elevated platform between said working floor and the lower end of said oven, means for heating the air on the interior of said oven, said oven having communication with the outer air near the upper end thereof whereby a slight upward movement of air is developed in said oven to maintain a relatively cool temperature near the loading and unloading positions between the floor and the oven, and a roof for the room or compartment having a skylight substantially over said platform.

16. A drying apparatus comprising a room or compartment having a working floor, a drying oven in said compartment having its lower end terminating above said floor, a plurality of racks for carrying the articles to be dried, means for advancing and guiding said racks upwardly into the interior of said oven and downwardly below the lower end thereof to enable the racks to be loaded and unloaded between the lower end of the oven and said working floor, means for heating the air in the interior of said oven, said oven having communication with the outer air near the upper end thereof whereby a slight upward movement of air is developed in said oven to maintain a relatively cool temperature near the loading and unloading positions

between the floor and the oven, a roof for 65 said room or compartment and ventilators in said roof for permitting the escape of the air under said roof and adjacent said oven.

17. In a drying apparatus, a traveling support, a rack for carrying sheets to be 70 dried carried by said support, said rack comprising a frame having a plurality of substantially U-shaped bent bars projecting outwardly therefrom and forming shelves for supporting the sheets to be dried. 75

18. In a drying apparatus, a rack for carrying sheets to be dried comprising a frame having a plurality of substantially U-shaped bent bars projecting outwardly therefrom and forming shelves for supporting 80 the sheets to be dried, and substantially vertical guard bars disposed between said shelves for preventing displacement of the sheets therefrom.

19. In a drying apparatus, a rack for carrying a plurality of sheets consisting of a frame having a plurality of substantially parallel shelves projecting therefrom arranged in transverse rows, and a pair of opposite gudgeons near the upper part of said 90 frame and from which said frame may be supported, said gudgeons being disposed forward of said frame and over said shelves to prevent undue tilting of the frames when loaded. 95

20. In a drying apparatus, a rack for carrying sheets to be dried comprising a frame having a plurality of shelves projecting outwardly therefrom for supporting the sheets to be dried, brackets projecting forwardly from said frame over said shelves, 100 and inclined tie bars attached to said brackets and extending downwardly and attached to the lower end of said frame.

21. In a drying apparatus, a rack for carrying sheets to be dried comprising a frame having a plurality of shelves projecting outwardly therefrom for supporting the sheets to be dried, brackets projecting forwardly from said frame over said shelves, 110 inclined tie bars attached to said brackets and extending downwardly and attached to the lower end of said frame, and gudgeons at said brackets for supporting said rack.

22. An apparatus of the class described comprising a compartment having a working floor, an oven located above the working floor and spaced apart therefrom, a conveyer located partially within the oven and extending partially below such oven, an elevated platform located adjacent the portion of the conveyer extending below the oven, and article supporting racks carried by the conveyer. 120

23. An apparatus of the class described comprising an elevated bottomless oven, a vertically disposed conveyer located partially within the oven and extending down-

ward below the oven, article carrying racks for the conveyer, and an elevated platform located adjacent the portion of the conveyer projecting below the oven.

5 24. An apparatus of the class described comprising an elevated oven, an elevated platform located beneath the oven, and a

series of article supporting racks carried by the endless conveyer and adapted in the travel of the latter to be carried to a point 12 below the elevated platform.

In testimony whereof I have hereunto set my hand.

WASHINGTON I. TUTTLE.
